(57) **CLAIM**

The ornamental design for an sticker extrusion for spacing wood, as shown and described.

DESCRIPTION

FIG. 1 is a perspective view of the sticker extrusion for spacing wood showing the new design;

FIG. 2 is a top view thereof, with the opposing bottom view being identical;

FIG. 3 is an end view thereof, with the opposing end view being identical; and,

FIG. 4 is a side view thereof, with the opposing side view being identical.

The broken lines in the drawings illustrate portions of the sticker extrusion for spacing wood which form no part of the claimed design. The sticker extrusion for spacing wood is shown in FIGS. 1, 2 and 4 with a symbolic break in its length. The appearance of any portion of the article between the break lines forms no part of the claimed design.
